SLING SHOT

Kalman Z. Huszar, Foster, Ohio

Application March 13, 1956, Serial No. 40,582

Term of patent 14 years

(Cl. D34—15)

FIG. 1.

FIG. 2.

FIG. 3.

FIG. 4.

Figure 1 is a top plan view of a sling shot, showing my new design;

Figure 2 is a side elevational view thereof;

Figure 3 is a front elevational view thereof; and

Figure 4 is a perspective view thereof.

The dominant features of my new design are shown in solid lines in the drawings.

I claim:

The ornamental design for a sling shot, substantially as shown and described.
